Primary Examiner—Bernard Ansher*Assistant Examiner*—Prabhakar Deshmukh*Attorney, Agent, or Firm*—W. Patrick Quast**[57]****CLAIM**

The ornamental design for a vacuum-packed foil package, as shown and described.

DESCRIPTIONFIG. 1 is a perspective view of a vacuum packed foil package showing my new design;
FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a bottom plan view of a second embodiment of FIG. 1;

FIG. 9 is a front elevational view of FIG. 8;

FIG. 10 is a right side elevational view of FIG. 8;

FIG. 11 is a rear elevational view of FIG. 8;

FIG. 12 is a left side elevational view of FIG. 8.

The top plan view of FIG. 8 embodiment is similar to as shown in FIG. 2.
